UNITED STATES PATENT OFFICE.

JOHN R. ANDERSON, OF MOLINE, ILLINOIS.

EXERCISER.

Application filed July 5, 1923. Serial No. 649,398.

To all whom it may concern:

Be it known that I, JOHN R. ANDERSON, a citizen of the United States, residing at Moline, in the county of Rock Island and State of Illinois, have invented certain new and useful Improvements in Exercisers, of which the following is a specification.

My invention particularly relates to an exerciser which can be permanently or detachably secured to a wall or the floor of a room and which can be used in a variety of exercises.

10 The main object of my invention is to provide an exerciser of simple and improved construction.

15 A more specific object of my invention is to provide an improved exerciser of the character described which may be adjusted to meet the strength of the user.

20 Other objects of my invention will become apparent as the detail description progresses, reference being had to the accompanying drawings, wherein—

25 Fig. 1 is a perspective view of an exerciser embodying the novel features of my invention.

Fig. 2 is a central longitudinal section taken through the exerciser shown in Fig. 1.

30 Fig. 3 is a section taken on line 3—3 of Fig. 2.

Fig. 4 is a side elevation of an exerciser and illustrates another form which my invention may take.

35 Fig. 5 is a section taken through line 5—5 of Fig. 4, and

Fig. 6 is a detail section taken through a ball and a shaft projecting therefrom, the ball and shaft being parts of the exerciser shown in Figs. 4 and 5.

40 Referring for the present to Figs. 1, 2, and 3, the reference character 10 designates a base forming a part of my improved exerciser. The base 10 is provided with an outwardly projecting flange 11 having apertures 12 permitting the base to be secured to a wall or the floor of a room by bolts or the like. It is apparent that the base 10 may be detachably or permanently secured in any desired position so as to meet the 45 particular desires of the user.

50 The base 10 is provided with an upwardly extending annular flange 13 having a spherical surface 14, which together with a spherical surface 15 of a plate 16 is adapted to form a socket for a ball 17 journaled therein. The plate 16 is loosely pivoted to the base

10 as indicated at 18, a bent plate 19 being provided for this purpose. The bent plate 19 is rigidly secured to the base 10 by means of a plurality of screws 20. The free end 60 of the loosely pivoted plate 16 is notched as at 21 to receive a boss 22 formed integral with the base 10 and furnishing guide means for the plate 16 in its movement. A pin 23 slidably journaled in the boss 22 provides 65 means, together with a helical compression spring 24 and a knurled nut 25, for yieldingly forcing the plate 16 toward the ball 17. The pin 23 has a portion 26 of rectangular cross section which is adapted to slide 70 in a similarly shaped aperture 27 in the boss 22. The helical compression spring has one end thereof resting against the plate 16 and the other end thereof resting against a head 28 formed upon the lower end of the 75 pin 23. The nut 25 is threaded upon the other end of the pin 23 and may be employed to increase or decrease the tension of the spring 24 so as to increase or decrease the pressure under which a friction lining 29 80 interposed between the plate 16 and the ball 17 will frictionally engage the ball 17. It will be noted that a friction lining 30 is also interposed between the angular flange 13 and the ball 17.

85 Projecting from the ball 17 is a shaft 32 which comprises a tapered plug 33 driven into the ball. Secured to the outer end of the tapered plug 33 is a tube 34 having at its upper end a hand grip 35 which is rotatably 90 journaled upon a sleeve 36 driven into the outer end of the tube 34. The axes of the tube 34, hand grip 35, and sleeve 36 are coincident. The hand grip 35 is held in place upon the sleeve 36 by means of a plug 37 95 driven into the outer end of the sleeve 36.

In the operation of the device, the user grasps the hand grip 35 and angularly displaces the movable elements of the exerciser about the center of the ball 17 against 100 the resistance of the frictional engagement between the ball 17 and the friction linings 29 and 30. The exerciser, as hereinbefore stated, may be secured either to a wall or the floor of a room, or to any other suitable object, and the user may employ the exerciser in a variety of exercises. The user, by means of the nut 25 and its attending mechanism, may adjust the pressure under which the friction linings 29 and 30 engage 105 the ball 17. It is readily understood that the exerciser may be adjusted to meet the 110

strength of a child, a woman or a man.

Referring now to Figs. 4, 5, and 6, I have shown an exerciser which embodies another form which my invention may take. This

5 exerciser has a base 10^a which comprises a base plate 10^b and a bracket 10^c. The bracket 10^c is rigidly secured to the base plate 10^b by means of a plurality of bolts 38. The base plate 10^b may be secured to 10 any suitable object. A spherical surface 39 provided in the bracket 10^c cooperates with a spherical surface 40 provided in a substantially cup-shape plate 41 to form a socket 42 which is adapted to receive a ball 43. 15 A friction lining 44 is interposed between the spherical surface 39 and the ball 43 and a friction lining 45 is interposed between the spherical surface 40 and the ball 43. Driven into the ball 43 is a tapered sleeve 47 forming a seat for one end of a shaft 48 disposed radially with respect to the ball.

The substantially cup-shape plate 41 is slidably mounted with respect to the bracket 10^c, a pair of pins 49 rigidly secured in the bracket 10^c being adapted to enter apertures 50 provided in the plate 41 and furnishing guide means therefor in its movement. The plate 41 is also slidably journaled upon a screw threaded pin 52 which 25 has its axis disposed parallel with respect to the axes of the pins 49, the axis of the screw threaded pin 52 being disposed radially with respect to the ball 43. The outwardly projecting end of the pin 52 is rigidly secured 30 in a bracket 53 by suitable means, as, for instance, a pin 54. The bracket 53 is mounted upon the base plate 10^b and secured thereto by screws 55. A helical compression spring 56, disposed around a lug 40 57 formed integral with the plate 41 and apertured to receive the pin 52, is arranged to yieldingly force the plate 41 toward the ball 43. One end of the compression spring 56 rests against the plate 41 and the other 45 end thereof rests against a nut 57 threaded upon the pin 52. The nut 57 is provided with a plurality of holes 58 providing means whereby a rod 59 may be employed to rotate the nut so as to increase or decrease the 50 force with which the spring 56 forces the plate 41 toward the ball 43. The rod 59 is preferably fastened to the pin 52 by a chain 60, the chain 60 serving to prevent loss of the rod.

55 The operation of the exerciser shown in Figs. 4, 5, and 6 is practically identical with the operation of the exerciser shown in Figs. 1, 2, and 3. The exerciser shown in Figs. 4, 5, and 6 may be detachably or permanently 60 secured to any suitable object, as heretofore stated, and the user may employ it in connection with a number of exercises. The nut 57 may be adjusted to cause the spring 56 to increase or decrease the pressure with 65 which the friction linings 44 and 45 engage

the ball 43. This construction will permit the user to vary the pressure of the friction linings against the ball to a point or value which will meet his or her strength.

As the exerciser may be employed in exercises in which the shaft is moved forwardly and backwardly in a single plane, the ball of the exerciser in these exercises may be considered as a member rotatably journaled with respect to the base of the 70 exerciser. However, the ball and socket construction which I have shown and described is advantageous in that the exerciser may be used in connection with a wider range of exercises than would be possible were 75 the exerciser constructed with a rotatable member which was only revoluble around a single axis of rotation. Moreover, by providing a single spring which may be adjusted by a single means to vary the pressure 80 exerted on the ball received within the socket I simplify the construction and operation of my device very materially in that a person desiring to vary the pressure 85 merely turns the nut 25 or 57 as the case 90 may be, the time and effort needed being thereby reduced to a minimum.

I am aware that changes in the form, construction and arrangement of parts may be made without departing from the spirit and 95 without sacrificing the advantages of the invention and I reserve the right to make all such changes as fairly fall within the scope of the following claims.

I claim:

1. An exerciser comprising a base, a member loosely mounted on said base and cooperating therewith to form a socket, means for yieldingly urging said member toward said base, means for adjusting said last 105 named means, a ball in said socket and a handle on said ball, said handle provided with a rotatable grip.

2. An exerciser comprising a base, guide means on said base, a member loosely mounted on said guide means for motion to and from said base, means yieldingly urging said member toward said base, said base and said member cooperating to form a socket, a ball in said socket, and a handle 115 on said ball.

3. An exerciser comprising a base, guide means on said base, a member loosely mounted on said guide means for motion to and from said base, means yieldingly urging said member toward said base, means for adjusting said last named means, said base and said member cooperating to form a socket.

4. An exerciser comprising a base, guide means on said base, a member loosely mounted on said guide means for motion to and from said base, means yieldingly urging said member toward said base, means for adjusting said last named means, said base 125 130

and said member cooperating to form a socket, a ball in said socket and a handle on said ball.

5. An exerciser comprising a base, guide means on said base, a member loosely mounted on said guide means for motion to and from said base, means yieldingly urging said member toward said base, means for adjusting said last named means, said base and said member cooperating to form a socket, a ball in said socket and a handle on said ball, said handle provided with a rotatable grip.

6. An exerciser comprising a base, a socket in said base, a ball in said socket, and means for moving said ball in said socket,

said means comprising a handle provided with a rotatable grip.

7. An exerciser comprising a base, a member loosely mounted on said base, said base and said member cooperating to form a socket, means on said base to guide said member, and a single resilient element urging said member toward said base.

8. An exerciser comprising a base, a member loosely mounted on said base, said base and said member cooperating to form a socket, means on said base to guide said member, a single resilient element urging said member toward said base and means to adjust said resilient element.

JOHN R. ANDERSON.
